United States Patent Office

Des. 222,231
Patented Oct. 12, 1971

222,231

DRAW BOLT OR SIMILAR ARTICLE

Samuel J. Holtzman, 8201 Symphony Drive,
Baltimore, Md. 21208

Filed Aug. 7, 1970, Ser. No. 24,364

Term of patent 14 years

Int. Cl. D8—06

U.S. Cl. D8—129

FIG. 1

FIG. 2

FIG. 3

FIG. 4

FIG. 5

FIG. 1 is a top plan view of a draw bolt or similar article embodying my new design;

FIG. 2 is a side elevational view as viewed from the right side of FIG. 1, the appearance of the opposite side being the same;

FIG. 3 is a front elevational view as viewed from the top of FIG. 1;

FIG. 4 is a rear elevational view as viewed from the bottom of FIG. 1; and

FIG. 5 is a bottom plan view.

I claim:

The ornamental design for a draw bolt or similar article, as shown and described.
